No. 757,985.

PATENTED APR. 19, 1904.

F. C. WATSON.
TRACTION ENGINE.
APPLICATION FILED AUG. 6, 1902.

NO MODEL.

UNITED STATES PATENT OFFICE.

FRANK C. WATSON, OF DES MOINES, IOWA, ASSIGNOR TO AVERY MANUFACTURING COMPANY, OF PEORIA, ILLINOIS, A CORPORATION OF ILLINOIS.

TRACTION-ENGINE.

SPECIFICATION forming part of Letters Patent No. 757,985, dated April 19, 1904.

Application filed August 6, 1902. Serial No. 118,661. (No model.)

To all whom it may concern:

Be it known that I, FRANK C. WATSON, a citizen of the United States, residing at Des Moines, in the county of Polk and State of Iowa, have invented certain new and useful Improvements in Traction-Engines, of which the following is a specification, reference being had therein to the accompanying drawings.

10 My invention relates to improvements in chain-drums for the steering mechanism of traction-engines and other vehicles, the object being to conveniently and securely attach the chain to the drum and to accurately guide both limbs of the chain as they are alternately taken up and let off in the steering operation, so as to prevent any overlapping of the chain one coil upon another, which would shorten the chain and tend to the breaking or disarrangement of the steering-gear.

15 The invention consists in the parts and combinations thereof hereinafter set forth.

In order to make my improvements more clearly understood, I have shown in the accompanying drawings means for carrying the same into practical effect without limiting the invention to the particular construction which I have delineated for the purpose of illustration.

20 In said drawings, Figure 1 is a plan view of a chain-drum and so much of the steering mechanism of a traction-engine as is necessary for a full illustration of the invention. Fig. 2 is a plan view of the drum on a larger scale. Fig. 3 is a sectional view on line III, Fig. 2. Fig. 4 is a side elevation of the mechanism shown in Fig. 1.

25 Referring to the drawings, A indicates the traction-wheels of the engine; *a*, the axle or axles of the same; B, the steering-wheels, and *b* the steering-axle, connected with the body C of the engine by vertical pivot at *c*.

30 D D' are the steering-chains, connected one with the off arm 1 of the steering-axle and the other with the near arm 2 through the medium of clamps or links *d*. The two chains are preferably connected by means of a short cross-chain *d'*.

E is a transverse drum-shaft mounted beneath the body of the engine in bearings F 50 and adapted to be rotated by worm-pinion G, keyed on the shaft, and worm H, engaging said pinion. The worm is fixed on a shaft I, extending rearwardly and upwardly, or in other desired direction, to the location of the 55 engineer, where it is provided with a steering-wheel J.

Fixed on or formed on (as by casting) the shaft E are chain-receiving enlargements K K', arranged, preferably, each a little to one side 60 of the middle of the shaft. While said enlargements may be connected or integral with each other, their connection through the middle portion of the shaft is sufficient, and said parts K K', together with the shaft, may be 65 said to constitute a single drum for both limbs of the steering-chain.

The chain D leads from the steering-axle over the top of the shaft E and the enlargement K' to a pair of ears 3 and 4, which are 70 perforated transversely at 5, so as to receive a bolt 6, parallel with the shaft E and passing through the end link of the chain D. In line with or formed with the ear 4 is the inner end of a helical flange *k*, which makes substantially one turn back and outward around the enlargement K' to a point about in line with the ear 3. The flange *k* is preferably cast with the enlargement K' and is arranged to direct the chain D outward as it is coiled on 75 the drum and cause the second coil of the chain as it is taken up to lie at the outer side of the ear 3 and of the previous coil. At the point where the drum member K' first receives the chain near the point of attachment 80 at 6 it is somewhat notched or recessed, as indicated at 7, such recess continuing around or nearly around the drum at the base and outer side of the flange *k*. From said recess the drum member somewhat increases in diameter, being preferably rounded, as shown, to the point where it receives the beginning of the second coil of the chain, from which point it gradually tapers outward, as shown at 8, and terminates in a cylindrical portion 9, the 85 whole drum member being of sufficient diam-

- eter and length to take up all the chain that may be necessary when the steering-wheels are turned to the utmost in steering the vehicle to the right. The shape of the drum member above described causes the chain to be gradually taken up more rapidly as the drum is turned in the direction indicated by the arrow and compensates for the simultaneous foreshortening of the axle-arm 1.
10. The detailed description above given of the drum member K' applies equally to the member K, they being counterparts in shape; but said members are reversely arranged upon the shaft E, as shown, the steering-chain D' being led below the shaft E and below the drum member K to its point of attachment at 6.
- What I claim is—
1. In a steering-gear for a vehicle, the combination of the steering-wheels, steering-chains connected at their outer ends to the steering-wheels, a winding-drum, flanges on the drum to which the ends of the chains are secured and adapted to direct the chain longitudinally of the drum as it is wound up, and means for rotating said drum, substantially as set forth.
  2. In a steering-gear for traction-engines, the combination of the steering-wheels, steering-chains connected therewith, a drum on which said chains are adapted to be wound having attaching means for the ends of the chains, and flanges on the drum leading helically from said attaching means around a portion only of the circumference of the drum and longitudinally thereof and terminating at points short of said attaching means, substantially as set forth.
  3. In a steering-gear for traction-engines, the combination of the steering-wheels, steering-chains connected therewith, and a drum on which said chains are adapted to be wound, said drum increasing in circumference along helical lines followed by the chains as they are wound up and thence tapering outwardly toward its ends, substantially as set forth.
  4. In a steering-gear for traction-engines, the combination of the steering-wheels, steering-chains connected therewith, and a drum on which said chains are adapted to be wound, said drum having chain-guiding helical flanges and recesses 7 at the bases of the flanges, substantially as set forth.
  5. A drum for a steering mechanism having a flange for guiding the steering-chain longitudinally of the drum as it is wound up and a radially-disposed projection arranged adjacent to one end of said flange and adapted to provide therewith parts between which the chain can be secured to the drum, substantially as set forth.
6. The drum for taking up the steering-chains of traction-engines, having chain-receiving parts which increase in diameter as described from the points where the chains are attached, and helical flanges on said chain-receiving parts.
7. The drum for taking up the steering-chains of traction-engines having ears to which the chains are adapted to be secured, each pair of ears having a helical flange leading from one ear around the drum to the other ear, substantially as set forth.
8. A drum for a steering mechanism having a helical flange for guiding the chain on the drum, and a radially-disposed projection arranged adjacent to one end of said flange on the side thereof with which the chain is adapted to engage, and means for securing the chain to the drum between said projection and flange, substantially as set forth.
9. A drum for a steering mechanism having a guiding-flange with one face of which the chain is adapted to engage, and projections on the drum to which the chain is secured arranged to direct the chain so that it will engage with the said face of the flange, substantially as set forth.
10. In a steering-gear for traction-engines, the combination of flexible steering connections, and a take-up drum for the same having two portions of its surface convexly shaped to compensate for the greater or less amount of chain to be taken up, and to prevent slackness or tightness of the chains, substantially as set forth.
11. A winding-drum for a steering mechanism having a winding-surface convex in longitudinal section, substantially as set forth.
12. A winding-drum for a steering mechanism having a winding-surface convex in longitudinal section and a guiding-flange on said surface, substantially as set forth.
13. A winding-drum for a steering mechanism having a spheroidal winding-surface, and a helical guiding-flange on said surface, substantially as set forth.
- In testimony whereof I affix my signature in presence of two witnesses.

FRANK C. WATSON.
